(57) **CLAIM**

The ornamental design for a bristle for a brush, as shown and described.

DESCRIPTION

FIG. 1 is a perspective view of a first embodiment of a bristle for a brush showing my new design;

FIG. 2 is an elevation view of FIG. 1;

FIG. 3 is a top plan view of FIG. 1;

FIG. 4 is a bottom plan view of FIG. 1;

FIG. 5 is a perspective view of a second embodiment of the bristle with only differences residing in the number and spaced arrangement of the rings of the bristle filament; and, FIG. 6 is an elevational view of FIG. 5.

The bottom end of the bristle is shown broken away to indicate indeterminate length.
